UNITED STATES PATENT OFFICE.

EDWARD J. RYAN, OF BUFFALO, NEW YORK.

DISPLAY-FORM.

1,077,560.

Specification of Letters Patent.

Patented Nov. 4, 1913.

Application filed June 30, 1913. Serial No. 776,480.

To all whom it may concern:

Be it known that I, EDWARD J. RYAN, a citizen of the United States, residing at Buffalo, in the county of Erie and State 5 of New York, have invented new and useful Improvements in Display-Forms, of which the following is a specification.

This invention relates to a detachable friction joint which is more particularly designed for use in connecting the articulated display forms or figures used in displaying garments in the show windows or rooms of stores.

The arms and hands of such figures which are usually made partly of wax have to be removed and replaced in the act of robing or disrobing the forms in order to prevent injuring or marring the same. The joints of this character as heretofore constructed were 20 such that they would soon become loose and not stay in the adjusted position, thereby not only causing the figures to assume awkward positions but also rendering the form liable to be injured.

It is the object of this invention to provide a joint for the form sections which will permit the same to be readily dismembered or assembled and also hold these sections reliably in any position to which the 30 same may be adjusted or posed.

In the accompanying drawings: Figure 1 is a vertical longitudinal section of a detachable friction joint for display forms embodying my invention. Fig. 2 is a horizontal section thereof. Fig. 3 is a vertical transverse section taken in line 3—3, Fig. 1. Figs. 4, 5 and 6 are perspective views of different members of the frictional joint between the display form sections.

Similar characters of reference indicate corresponding parts throughout the several views.

Although this detachable frictional joint may be employed in various parts of the 45 display form where it is desired to produce an articulate connection the same is here shown as applied to the upper and lower form sections 1, 2 of an arm which are adapted to be detachably connected and 50 also held frictionally in any position to which the same may be adjusted.

At the upper end of the lower arm section the same is provided with a pivot head 3 which is preferably of spherical form 55 and secured to the upper end of the lower arm section by means of a screw threaded

shank 4 engaging with a correspondingly threaded opening in the lower form section. On its upper side the lower pivot head is provided with a radial diametrical slot 5 60 which receives an upper pivot head 6 preferably constructed in the form of a flat disk. This pivot disk and pivot head are connected by a transverse pivot bolt, screw or pintle 7 extending diametrically through 65 the lower and upper pivot heads so that these two pivot heads may be turned one relatively to the other about the pivot pin 7. At its outer edge the upper pivot head is provided with a coupling shank 8 which terminates at its rear end in a cone-shaped head 9 which tapers rearwardly and has a forwardly facing shoulder 10.

Within a recess 11 formed in the upper arm or form section 1 at a distance from its 70 front end is arranged the catch which is adapted to engage with the coupling shank and operates as part of the means for detachably connecting the two form sections. This catch preferably comprises two levers 80 12, 12 which are arranged lengthwise in said recess adjacent to opposite sides thereof and flush with the outer side of the upper form section, two jaws 13 projecting inwardly toward each other from the front ends of 85 the levers and having their opposing faces beveled so that they taper inwardly, and two pairs of pivot lugs 14 formed on the central parts of these catch levers and projecting inwardly therefrom so that they 90 overlap one another. These overlapping lugs of the catch levers are connected by a transverse bolt, screw or pintle 15 passing through these lugs and the adjacent parts of the upper form section, as shown in Figs. 95 1 and 2. The catch levers are yieldingly turned in a direction which will cause their jaws to approach each other this being preferably effected by means of a single spring 16 interposed between the arms of the catch 100 levers and confined against displacement on these levers by means of lugs 17 formed on the inner sides of the rear arms and entering the end coils of the spring.

By pushing the tapering head of the coupling shank inwardly between the two jaws of the catch levers these jaws are first separated by the wedging action of the tapering rear face of the conical head on the shank and after the shoulder of this head passes inwardly beyond the jaws the latter again move toward each other under the action of 110

the spring 16 and engage with the shoulder 10, thereby connecting the upper and lower arm or form sections. When it is desired to detach these form sections it is only necessary to press the inner or rear arms of the catch levers together, thereby separating the jaws on the front arms of the same and permitting the coupling head 9 to be withdrawn from between the same and the two form sections to be wholly disconnected. While the form sections are thus connected the same can be turned relatively to each other about the transverse axis furnished by the transverse pin and bolt 7 and the same can also be turned about the longitudinal axis furnished by the coupling shank 8 which can turn between the jaws of the catch levers, thereby providing for a universal joint which permits the two form sections to be adjusted in any position relatively to each other which may be required for properly positioning the form to display the garment to the best advantage.

In order to hold the joint between the upper and lower pivot heads in place frictionally the bolt 7 passing transversely through the same may be tightened as much as desired for pressing the two jaws formed by the bifurcated lower pivot head against opposite sides of the disk shaped upper pivot head.

In order to hold the longitudinal coupling shank 8 frictionally in the various positions to which the same may be posed or adjusted when turned about its axis a friction device is provided which permits of readily connecting or disconnecting the upper and lower form sections without interfering with this friction device. In its preferred form this last mentioned friction device is constructed as follows:

18 represents a sleeve provided with a flat sided opening 19 in the center or interior thereof which receives a correspondingly flat sided enlargement or hub 20 formed on the central part of the coupling shank between the upper pivot head and the tapering coupling head. In the preferred form of this sleeve its opening is square and the coupling hub is of corresponding form in cross section, as shown in Fig. 3. On its outer side the friction sleeve 18 is provided with a circumferential intermediate friction disk 21.

22, 23 represent inner and outer friction disks which are arranged on opposite sides of the intermediate friction disk and provided respectively with circular openings 24, 25 in which the inner and outer ends of the friction sleeve turn. Washers or disks 26 of fiber or similar friction material are preferably interposed between opposite sides of the intermediate disk and the inner and outer disks.

65 The inner friction disk may be secured to

the upper form section by any suitable means but preferably by means of two retaining arms 27 which project rearwardly from the inner friction disk on diametrically opposite sides thereof and along the walls from the recess 11 and provided at their rear ends with openings 28 which receive the pivot bolt 15 which connects the catch levers. The outer friction disk is adjustably connected with the inner friction disk by means of a plurality of adjusting screws 29 extending past the peripheral edge of the intermediate disk, as shown in Figs. 1, 2 and 3. Upon tightening the screws 29 the intermediate disk is gripped between the inner and outer disk, thereby frictionally resisting the turning movement of the intermediate disk, and also resisting the turning movement of the coupling shank and the parts connected therewith inasmuch as this coupling shank by reason of its square hub engaging with the correspondingly shaped opening in the sleeve is interlocked with the intermediate disk. The two form sections, however, are capable of being freely connected or disconnected without interfering with the upper friction mechanism inasmuch as the square hub of the coupling shank is free to slide in and out of the friction sleeve in the act of inserting the coupling shank between the catch levers or detaching the same therefrom. These means of detachably connecting the two form sections and holding the same frictionally in their adjusted position are exceedingly simple and inexpensive, they are not liable to get out of order, and they permit of quickly connecting and disconnecting the form sections as well as reliably adjusting them to any desired position or pose.

I claim as my invention:

1. A display form comprising two form sections, a coupling shank arranged on one of said sections, a catch arranged on the other section and engaging with said coupling shank, and means for frictionally retarding the rotation of said shank relatively to said catch comprising an intermediate friction member detachably connected with said shank, and two friction members engaging with opposite sides of said intermediate member and connected with said form section on which said catch is mounted.

2. A display form comprising two form sections, a coupling shank arranged on one of said sections, a catch arranged on the other section and engaging with said coupling shank, and means for frictionally retarding the rotation of said shank relatively to said catch comprising an intermediate friction disk detachably connected with said shank, an inner friction disk engaging with the inner side of said intermediate disk and connected with the form section on which said catch is mounted, and an outer friction disk engaging with the outer side of said

intermediate disk and adjustably connected with said inner disk.

3. A display form comprising two form sections, a coupling shank arranged on one of said sections, a catch arranged on the other section and engaging with said coupling shank, and means for frictionally retarding the rotation of said shank relatively to said catch comprising a square hub on 10 said coupling shank, a sleeve provided internally with a square opening which receives said hub and externally with an intermediate friction disk, an inner friction disk connected with the form member on which 15 the catch is mounted and bearing against the inner side of said intermediate disk and having an opening which receives the inner end of said sleeve, and an outer friction disk connected with said inner disk and bearing 20 against the outer side of said intermediate disk and having an opening which receives the outer end of said sleeve.

4. A display form comprising two form sections, a pivot pin mounted on one of said 25 form sections, two catch levers pivoted on said pin, a coupling shank connected with the other form section and having a tapering head engaging with said catch levers and a square hub in front of said head, an

intermediate friction disk having a square 30 opening which receives said hub, an inner friction disk engaging with the inner side of said intermediate disk and provided with arms which connect with said pivot pin, and an outer friction disk engaging with the 35 outer side of said intermediate disk.

5. A display form comprising two form sections, a pivot pin mounted on one of said form sections, two catch levers pivoted on 40 said pin, a coupling shank connected with the other form section and having a tapering head engaging with said catch levers and a square hub in front of said head, an intermediate friction disk having a square 45 opening which receives said hub, an inner friction disk engaging with the inner side of 50 said intermediate disk and provided with arms which connect with said pivot pin, an outer friction disk engaging with the outer side of said intermediate disk and adjusting screws connecting said inner and outer disks.

Witness my hand this 25th day of June, 1913.

EDWARD J. RYAN.
